UNITED STATES PATENT OFFICE.

CARTER W. BRYAN, OF KANSAS CITY, MISSOURI.

HANDLE FOR ORANGE-BOXES, &c.

SPECIFICATION forming part of Letters Patent No. 313,051, dated March 3, 1885.

Application filed August 7, 1884. (No model.)

To all whom it may concern:

Be it known that I, CARTER W. BRYAN, of 5
Kansas City, Jackson county, Missouri, have
invented a new and Improved Handle for
Orange-Boxes, &c., of which the following is
a full, clear, and exact description.

The device is made of wire and a piece of
wood or its equivalent. One end of the wire is
passed around the piece of wood and then twisted
10 around the main portion of the wire, and the
other end is bent to form an eye or loop, and
also twisted about the main portion of the
wire. A staple is driven through the eye thus
formed, for the purpose of securing the handle
15 to boxes for oranges, and other boxes and ar-
ticles which are carried by hand.

In the drawings, Figure 1 represents the
handle ready for attachment; Fig. 2, the same
attached and ready for use.

20 A is a piece of wood serving as a hand-hold,
and C a shank provided with an eye, B,
through which a staple, D, is passed and
driven into the wood E, which may be the end,

side, or top of box. The handle, being T-
shaped, requires only one connection. The 25
shank can be made of light and cheap wire,
and the whole device produced at such a very
small cost that the expense of attaching it to
boxes and various cheap articles is scarcely
30 appreciable.

What I claim is—

A handle consisting of twisted wire with a
wooden hand-hold or its equivalent in one end
and an eye formed in the opposite end loosely
35 interlocked with a fastener capable of pierc-
ing the material of the article to be carried,
whereby the handle may be attached and a
decided hold obtained, substantially as and
for the purposes described.

In testimony whereof I affix my signature in 40
presence of two witnesses.

CARTER W. BRYAN.
